UNITED STATES PATENT OFFICE.

JUAN ALBERTO VALDERRAMA RICORDI, OF NEW YORK, N. Y.

PROTECTING APPARATUS FOR SHIPS.

1,355,267.

Specification of Letters Patent.

Patented Oct. 12, 1920.

Application filed June 27, 1918. Serial No. 242,181.

To all whom it may concern:

Be it known that I, JUAN ALBERTO VALDERRAMA RICORDI, a citizen of the Republic of Peru, residing at New York city, county 5 and State of New York, U. S. A., have invented new and useful Improvements in Protecting Apparatus for Ships, of which the following is a specification.

My invention relates generally to an apparatus for protecting moving or stationary objects from projectiles or the like, and is more particularly adapted for the protection of ships from torpedoes, although it is not limited to this adaptation.

15 An object of my invention is the provision of a protecting apparatus for ships which will deflect a torpedo from its course without exploding the same and sufficiently to prevent it from striking the ship.

20 Another object of my invention is the provision of a protecting apparatus which will not retard the speed of the ship, but will, on the contrary, assist in the propulsion thereof.

25 I will describe one form of apparatus embodying my invention, and will then point out the novel features thereof in claims.

In the accompanying drawings,

Figure 1 is a view showing in side elevation a ship having applied thereto one form 30 of apparatus embodying my invention;

Fig. 2 is a view showing in top plan the apparatus shown in Fig. 1, also applied to a ship;

35 Fig. 3 is an enlarged detail view showing in transverse section a portion of a ship with the apparatus shown in the preceding views in end elevation;

Fig. 4 is a fragmentary plan view of the 40 apparatus shown in the preceding views;

Fig. 5 is a detail view showing in end elevation one form of housing for the apparatus, embodying my invention;

Fig. 6 is a fragmentary view showing in 45 side elevation the apparatus in folded position within the housing;

Figs. 7 and 7^a, respectively, are a side view and an end elevation of one form of link embodying my invention;

50 Figs. 8 and 8^a, respectively, are views showing in side elevation and top plan one form of pulley embodying my invention;

Figs. 9 and 10 are diagrammatic views 55 illustrating the principle of my invention;

Fig. 11 is a sectional view, taken on the line 11—11 of Fig. 7.

Similar reference characters refer to similar parts throughout the several views.

In carrying out my invention, I provide 60 a pair of endless belts arranged on opposite sides of a ship and which have portions thereof submerged to intercept and deflect, and thus prevent a torpedo from striking the ship. The portions of the belts which 65 are submerged are arranged one behind the other and are continuously movable in a direction opposite to the direction in which the ship is traveling, so that they assist in the propulsion of the ship when traveling 70 faster than the ship. The inner belt is adapted to travel at a speed approximately equal to one half of the speed of the torpedo, while the outer belt travels at the same speed as a torpedo. The outer belt is 75 designed to permit the torpedo to pass therethrough but, by virtue of its movement, it deflects the torpedo sufficiently so that it will strike the innermost belt at the most advantageous angle to allow the inner belt 80 to carry the torpedo rearwardly of the ship. The entire apparatus may be lifted from the water when not in use and housed to prevent mutilation thereof.

Referring first to Figs. 1 and 2, S designates a ship to the opposite sides of which are applied the torpedo protecting apparatus indicated generally at A. However, to simplify the drawings, I have shown only one of such apparatus. As here shown, the apparatus A comprises a pair of endless belts or screens B and C which are trained around pulleys D, secured to the side of the ship S and pulleys D' supported by beams 10 and 10^a, pivoted to the side of the ship for universal movement. With the apparatus A in the operative position, as shown in Figs. 1 and 2, the pulleys D and D' for each belt B and C are located at the corners of a rectangle and when power is applied to the 95 pulleys, the belts will be driven in the path of a rectangle. As shown in Fig. 2, the belt C is arranged within the belt B and is disposed in spaced parallel relation thereto throughout its entire length. As shown in Fig. 1, the pulleys D are disposed in a plane 100 above the water line of the ship S, while the pulleys D' are disposed below the same. By virtue of this arrangement of pulleys, the inner stretches of the belts B and C 105

110

travel alongside of the ship and out of the water while the lower stretches travel in the water and at a suitable distance from the side of the ship, which in practice is about 5 45 feet, so that, in the event a torpedo explodes at the belts, the ship will not be harmed.

To permit the belts B and C to follow such a course during movement, each belt is 10 composed of a pair of spaced endless cables 11 which are connected at regular spaced intervals by vertical links 12. As shown in Fig. 4, the links 12 of the belt B are so spaced that a torpedo can pass through the 15 belt, but the links 12 of belt C are spaced apart a distance equal to only one-half of the distance between the links of belt B, so that a torpedo cannot pass therethrough. As shown in Figs. 7 and 7^a, each link 12 20 comprises a pair of telescopic sections *a* and *b*, the upper section *a* receiving the lower section *b*, and both sections being of ovate formation to present the least possible resistance when traveling through the water 25 and the greatest possible mechanical resistance to a torpedo. The ends of each link 12 are pivoted at *c* to a bracket *d*, which latter is secured to its respective cable 11 by means of fastening member *e*. It will be 30 obvious that with belts B and C constructed as described, each belt when let down into operative position incloses a substantially rectangular space at the side of the vessel, as indicated in plan in Fig. 4, the space inclosed by the belt C being within the space inclosed by the belt B. By reason of this construction the belts will be driven, as hereinbefore stated, in the path of a rectangle. As shown in Fig. 3, the pulleys D 35 are spaced apart a distance less than the pulleys D', so that the belts traveling from the pulleys D' to the pulleys D are gradually contracted to about half their width and maintain this contracted position while 40 traveling from the rear pulleys D to the front pulleys, thus occupying a comparatively small space at the side of the vessel. Obviously, such a contraction of the belt is 45 due to the telescopic links 12, and it is to be understood that the links 12 are so constructed that they will freely move to extended position after having passed from the pulleys D at the forward end of the apparatus, so that the belt will assume its normal width when traveling through the 50 water.

As shown in Figs. 8 and 8^a, the pulleys D' are rotatably mounted on studs carried at the ends of the beams 10 and 10^a and 60 the periphery of each pulley is grooved and provided at intervals with notches to accommodate the brackets *d*.

As shown in Fig. 3, the pulleys D are mounted on brackets K, secured to the sides 65 of the ship S, and each set of pulleys at the

opposite ends of the apparatus is driven in synchronism by means of an electric motor M. The pulleys D for the belts B and C are provided with gears P and P' respectively, and the gears for the lower pulleys are 70 driven by means of an endless chain P² which extends through an opening in the side of the ship S and which is trained around a driving gear fixed to the shaft of the motor M. The upper gears are likewise 75 driven by a chain P², but this chain is trained about a gear P⁴ shown in dash lines in Fig. 4, fixed to a pintle P⁵. The pintle P⁵ is operatively connected to the shaft of the motor M by a connecting rod P⁶, which 80 is connected at its opposite end for universal movement to the pintle and shaft as shown. It is to be noted that the gear ratio between the gears P and P' is such that the rate of speed at which the belt B 85 is driven is double the speed of the belt C. The purpose of these relative speeds of the belts will be described hereinafter. For the purpose of closing the openings on the side of the ship S through which the chains 90 P² extend, I provide casings L, as shown in Fig. 3.

The motors M are adapted to be controlled by any suitable means from the bridge of the ship, so that the operator may control 95 the speed of the belts B and C in accordance with the speed of a torpedo.

For the purpose of lifting the lower stretches of the belts B and C and the associated mechanism out of the water, I provide a plurality of cables 13, one for each pair of beams 10 and 10^a. These cables are actuated by motor-operated windlasses 14, and, as shown in Fig. 2, each cable 13 has its intermediate portion trained about its 100 respective windlass. It then passes in opposite directions around pulleys 15 mounted on the ship S, and the ends are secured to the adjacent beam 10, as shown in Figs. 8 and 8^a. Obviously, when the windlasses 14 110 are rotated in a clockwise direction, as viewed in Fig. 2, the beams 10 and 10^a, and consequently the apparatus supported thereby, are moved upwardly and rearwardly to the side of the ship so as to occupy the position shown in Fig. 6. The beams 10 and 10^a are held in their proper relative positions at the side of the ship by means of struts T, as shown in Fig. 1.

To properly house the inner stretches of 120 the belts B and C during operation of the apparatus, and to house the entire apparatus during a rough sea to avoid mutilation thereof, I provide a plurality of housings, designated generally at H, such housings 125 being arranged end to end so as to form a substantially continuous wall as shown in Fig. 6. As shown in Fig. 5, each housing comprises a bottom section 16 pivoted at 17 to the side of the ship S, and an outer sec- 130

tion 18 pivoted to section 16 at 19. When the housings H are in the folded or active position, as shown in Fig. 5, the sections 16 and 18 occupy horizontal and vertical positions respectively, and thus provide a three-sided chamber one side being formed by the side of the ship, to thoroughly protect the apparatus from the action of the waves. When the housings are in the extended or collapsed position, the sections 16 and 18 lie contiguous to the sides of the ship S, as shown in Fig. 3.

To move each housing H from extended to folded position, I provide a cable 20, the outer end of which is secured to the rod 21, fixed to the outer section 18. The cable 20 is then trained around a pulley 22 mounted on a standard 23 carried by the bottom section 16, and it then passes up to a suitable mechanism (not shown) for actuating the cable. By this arrangement, the housing can be easily moved from extended to folded position, and in practice it is preferable to provide means to actuate all of the housings simultaneously and to control such means from the bridge of the ship.

The operation of the apparatus is as follows:

With the apparatus in the operative position, as shown in Figs. 1 and 2, the lower stretches of the belts B and C are submerged, while the upper stretches thereof are disposed between the housings H and the side of the ship. Power is now applied to all the pulleys D through the motors M thus causing the belts B and C to travel in the direction of the arrow, as indicated in Fig. 2. As previously stated, the belt B travels at double the speed of the belt C, while the latter travels at a speed approximately equal to one half the speed of a torpedo. The average torpedo travels at a speed of from 30 to 35 miles per hour, so that the belt C will travel at a rate of from 15 to 18 miles per hour, while the belt B will travel at the rate of from 30 to 35 miles per hour. With the belts traveling at these relative speeds, let us suppose that a torpedo strikes the apparatus: it will engage the belt B first and, because of the distance between the links 12 of the belt B, the torpedo will pass through the belt B into engagement with the belt C. However, because of the rapid speed at which the belt B is moving, the link next in the rear of the torpedo is caused to engage the side of the torpedo, thus deflecting the same to the right as illustrated in Fig. 9 and, upon further continued movement of the belt, the torpedo is caused to assume the position shown in Fig. 10. With the torpedo thus deflected, it strikes the belt C, not at right angles, but at an acute angle, so that the belt C, moving in the same general direction as the torpedo, carries the torpedo rear-

wardly and, in so doing, tends to cause the same to assume a position parallel to the belt, as indicated in dash lines in Fig. 10. Should the torpedo, however, owing to the influence of the gyroscope, attempt to resume its original direction, it will be prevented from so doing by reason of the fact that the space between the traveling belts B and C is too narrow, and therefore the torpedo will be carried by the belts clear of the ship before it can resume its original direction. Thus the torpedo is completely deflected out of the path of the ship.

At the rear end of the apparatus, suitable means (not shown), such as a net, may be provided for trapping the torpedo; or it may be left free to float to the rear of the ship.

In the case of an extremely heavy sea or when the ship is entering a port, the entire apparatus may be easily lifted to the side of the ship by first lowering all of the housings H to the position shown in Fig. 3, then operating the windlasses to move the entire apparatus to the side of the ship, whereupon they are returned to their normal positions and the entire apparatus completely housed.

Although I have herein shown and described only one form of apparatus embodying my invention, it is to be understood that various changes and modifications may be made herein without departing from the spirit of this invention and the spirit and scope of the appended claims.

What I claim is:

1. A protector for ships comprising means for deflecting a torpedo from its course, and means for deflecting the torpedo further to cause the same to occupy a position away from the hull of the ship, both of said means being constantly movable at predetermined speeds in a direction opposite to the direction in which a ship is traveling.

2. A protector for ships comprising means for deflecting a torpedo from its course, and means for deflecting the torpedo further to cause the same to occupy a position away from the hull of the ship, both of said means being movable at different speeds relatively to each other and in the same direction.

3. A protector for ships comprising a pair of endless belts, said belts being spaced apart and having one stretch thereof submerged, and means for moving said belts at different predetermined speeds and in such direction that the submerged stretches move in the opposite direction to that in which the ship is traveling.

4. A protector for ships comprising a pair of endless belts, said belts being arranged one within the other, means for movably supporting said belts so that the outer stretch only of each belt is submerged, and

70

75

90

100

95

105

115

120

125

130

means for rotating said belts at different predetermined speeds and in such direction that the submerged stretches move in a direction opposite to the travel of the ship.

5. A protector for ships, comprising a pair of endless belts made up of articulated links, means for driving said belts in the path of a rectangle, and means for causing said belts to travel at predetermined speeds.

6. A protector for ships comprising means for deflecting a torpedo from its course, means for deflecting the torpedo further from its course, means for elevating both of said means to the side of a ship, and means for housing said deflecting means.

7. In combination, a ship, means for deflecting a torpedo away from the hull of the ship, housings carried by the ship and adapted to assume a position about said means for protecting the latter, and means for moving said housings into protecting position.

8. A protector for ships comprising an endless means movable at a rate of speed approximately equal to the speed of a torpedo, and a second endless means between

the first means and the ship and movable at one half the speed of the first means and in the same direction, and the first means being constructed to permit the passage of a torpedo while the second means is constructed to prevent the passage thereof.

9. A torpedo guard comprising movable mechanisms relatively associated to define an intervening space therebetween, one of said mechanisms having interstices therein to permit torpedoes to enter, and the other mechanism serving to intercept the normal course of the torpedo and means for moving the mechanisms in the same direction at different relative speeds.

10. In combination, a ship, a torpedo guard comprising a pair of endless screens, means for continuously moving said screens, collapsible housings carried by said ship, means for lifting said screens into close proximity to the side of the ship, and means for moving said housings into position to inclose said screens when in lifted position.

In testimony whereof I have signed my name to this specification.

JUAN ALBERTO VALDERRAMA RICORDI.
